DISPLAY STAND

Robert Paul Benz, 410 Ivywood Drive,
Oxnard, Calif. 93030

Filed Oct. 14, 1968, Ser. No. 13,989

Term of patent 14 years

Int. Cl. D6—01

U.S. CL. D80—9

FIG. 1

FIG. 2

FIG. 3

FIG. 4

FIG. 1 is a perspective view of a display stand with shelves showing my new design;

FIG. 2 is a front elevational view thereof, the rear view being the same as the front as shown;

FIG. 3 is an elevational view taken from the side opposite to that shown in FIG. 1; and

FIG. 4 is a top plan view thereof.

I claim:

The ornamental design for a display stand, substantially as shown and described.
